US00D440069S

(12) **United States Design Patent**
Lechman

(10) Patent No.: **US D440,069 S**
(45) Date of Patent: **** Apr. 10, 2001**

(54) **MODULAR TRAPEZOIDAL CLASSROOM DESK**

(74) *Attorney, Agent, or Firm*—Olson & Hierl, Ltd.

(75) Inventor: **John N. Lechman**, Effingham, IL (US)

(57) **CLAIM**

(73) Assignee: **Nova Solutions, Inc.**, Effingham, IL (US)

The ornamental design for a modular trapezoidal classroom desk, as shown and described.

(*) Notice: This patent is subject to a terminal disclaimer.

DESCRIPTION

(**) Term: **14 Years**

(21) Appl. No.: **29/127,577**

(22) Filed: **Aug. 8, 2000**

Related U.S. Application Data

(62) Division of application No. 29/089,124, filed on Jun. 8, 1998, now Pat. No. Des. 429,088.

FIG. 1 is a perspective view of the inventive design for a modular trapezoidal classroom desk;

(51) LOC (7) Cl. **06-04**

FIG. 2 is a top plan view of the design of FIG. 1 with the left and right back side doors in their closed positions;

(52) U.S. Cl. **D6/422**

FIG. 3 is a left side (relative to FIG. 1) elevational view of the design of FIG. 1;

(58) Field of Search D6/422-428, 436;

FIG. 4 is a right side (relative to FIG. 1) elevational view of the design of FIG. 1;

108/60, 64, 91, 111; 312/194, 195, 196,

FIG. 5 is a front side (relative to FIG. 1) elevational view of the design of FIG. 1 with the left and right back side doors in their closed positions;

203, 223.3, 240, 258, 270.1-270.3, 249.4

FIG. 6 is a back side (relative to FIG. 1) elevational view of the design of FIG. 1 with the left and right back side doors in their closed positions;

(56) **References Cited**

FIG. 7 is a bottom plan view of the design of FIG. 1 with the left and right back side doors in their closed positions;

U.S. PATENT DOCUMENTS

FIG. 8 is a view of the design of FIG. 1 similar to FIG. 2 but with the left and right back side doors in their open positions;
